UNITED STATES PATENT OFFICE.

GEORGE KEITH AND WILFRED AMBROSE WHATMOUGH, OF LONDON, ENGLAND.

MEANS FOR CONTROLLING THE SUPPLY OF COMBUSTIBLE MIXTURE TO INTERNAL-COMBUSTION ENGINES.

1,422,987.

Specification of Letters Patent. Patented July 18, 1922.

Application filed May 3, 1918. Serial No. 232,421.

To all whom it may concern:

Be it known that we, GEORGE KEITH and WILFRED AMBROSE WHATMOUGH, both subjects of the King of the United Kingdom of

5 Great Britain and Ireland, and residing at London, England, have invented a certain new and useful improvement in means for controlling the supply of combustible mixture to internal combustion engines, of which

10 the following is a specification.

This invention relates to means for controlling the supply of combustible mixture to internal combustion engines, for example to engines of automobile vehicles.

15 One object of the invention is to ensure approximately constant quality of the mixture, irrespective of the speed of the engine, of the atmospheric pressure or other circumstances liable to affect the quality.

20 Another object is to render practicable the employment of combustible gas or vapour from any source—for example of vapour produced by vaporization of a heavy hydrocarbon.

25 Broadly, the invention consists in the arrangement of a governor operated by pressure functions of the components of the combustible mixture and adapted to maintain a difference of pressure across the fuel supply

30 regulator proportionate to the difference between the pressure at the point of admixture of fuel and air and the pressure at some other selected point in the induction pipe system.

35 For convenience we shall assume for the purpose of the following description that the combustible medium to be admixed with air is vapour obtained by vaporization of liquid, say a liquid hydrocarbon.

40 To effect vaporization, there is provided a vaporizer which may be conveniently heated by the exhaust gases from the engine or otherwise and to which the liquid to be vaporized is fed without addition of air at

45 a rate dependent on the demand.

The fuel so obtained, no matter what be the pressure in the vaporizer, is brought to a given pressure, lower than that in the vaporizer, by means of a governor device,

50 say a diaphragm governor, and thence led past a valve or obturator adjustable in accordance with the desired proportions constituting the mixture, and injected or induced to flow into the induction pipe or

55 manifold through which is also inspired

the air for combustion; the point of introduction of the fuel being desirably located as near the engine as practicable, to reduce liability to condensation.

A constriction may be formed in the induction pipe in order to increase the difference of pressure between the throttle valve and the point of admission of the fuel.

If the throttle valve be located more remote from the engine than the point of fuel admission, a connection from the induction pipe to the back of the governor diaphragm may be taken from any point of the induction pipe, whereby the quality of the mixture will be automatically controlled in such wise as to ensure substantial uniformity of the quality of the mixture.

The pressure set by the governor can be adjusted within limits by so disposing the orifice (at the induction pipe end) of the connection between the induction pipe and the back of the diaphragm, as to face towards or away from the incoming current of air, or to occupy any position between the two extremes.

The figure of the accompanying drawing illustrates diagrammatically by way of example one form of apparatus according to the invention.

Referring to the drawing, A denotes the vaporizer which is located within an enlargement of the exhaust pipe B, and to which the liquid to be vaporized is led by way of the pipe C. D denotes the diaphragm of the automatic mixture controller, the diaphragm D being connected by a spindle to a valve E controlling the outlet from the vaporizer A. F denotes a pipe connecting the upper part of the diaphragm chamber to the induction pipe G at a point nearer the engine than the controlling valve located at H.

Air is admitted to the induction pipe G through a pipe I, and as the admission of air is controlled by the valve at H said valve serves the purpose of a throttle valve, as the amount of combustible vapor passing to the engine must depend upon the amount of air admitted to the induction pipe.

The end J of the pipe F inside the induction pipe G may be bent and so constructed that it may be turned to face towards or away from the flow of air passing through the induction pipe G, whereby to vary the pressure on the top of the diaphragm D under any given running conditions of the engine.

2
 K denotes a constriction or choke-bore formed on the induction pipe and designed to establish a sufficient difference of pressure between that point of the induction pipe at 5 which the pipe J is introduced and that point at which the vapour is admitted. L denotes a tube along which the vapour passes after being governed by the valve E; the tube L is preferably located within the exhaust pipe 10 B so as to reduce the liability to condensation. M denotes an obturating member whence the vapour passes into the induction pipe G by way of an extension N which may take the form of a perforated tube. The proportion 15 of vapour to air in the mixture is set by adjustment of the obturating member M.

The induction pipe G opens into the intake manifold O as does also the extension N of the obturating member M.

20 From the foregoing it will be understood that vapor admission valve E will be controlled by the suction in the induction pipe through the obturating member M, fuel pipe L and the governing diaphragm D connected with 25 said valve E. In other words as the suction in the induction pipe is increased the valve E is lowered thus admitting more fuel to the pipe L.

What we claim is:—

30 1. In combination, an induction pipe through which a mixture of fuel and air is sucked to an internal combustion engine, a passage for exhaust gases, a vaporizer in said passage, a tubular connection between 35 said vaporizer and said induction pipe, said tubular connection extending through said exhaust passage, a valve serving to control communication between said vaporizer and said tubular connection, an obturating member 40 for regulating delivery of vapor from said tubular connection to said induction pipe, a chamber between and in communication with said vaporizer and said induction pipe, and an automatically operating governor member movable in said chamber, said 45 governor member being operatively connected to said valve and being controlled by the pressure in said induction pipe.

2. In combination with an induction pipe 50 through which a mixture of fuel and air is sucked to an internal combustion engine, a valve controlling the admission of air to said pipe, a vaporizer for fuel, a tubular connection between said vaporizer and said induction pipe, an obturating member serving to regulate the supply of fuel through 55 said connection to said pipe, and a governor device arranged between said vaporizer and said induction pipe, said vaporizer, connection, obturating member and governor 60 device being arranged to be heated by the exhaust from said engine, said governor device being automatically controlled by the suction or flow of the components of the 65 mixture and adapted to maintain a dif-

ference of pressure across said obturating member proportionate to the difference between the pressure at the point of entry of fuel into said pipe and the pressure at some other selected point.

3. In combination, an induction pipe through which a mixture of fuel and air is sucked to an internal combustion engine, a valve controlling the admission of air to said pipe, a vaporizer for fuel, a tubular connection between said vaporizer and said pipe, a manually adjustable obturating member for regulating the delivery of fuel from said tubular connection to said pipe, a governor comprising a member arranged between said vaporizer and said induction pipe and which member is automatically controlled by the pressure of the mixture in said induction pipe, and a valve operatively connected to said member, said valve being adapted to control the passage of fuel from said source of supply to said tubular connection, said vaporizer, connection, obturating member and governor being arranged to be heated by the exhaust from said engine.

4. In combination, an induction pipe through which a mixture of fuel and air is sucked to an internal combustion engine, a valve controlling the admission of air to said induction pipe, a vaporizer, a tubular connection between said vaporizer and said induction pipe, a valve serving to control communication between said vaporizer and said tubular connection, a manually adjustable obturating member for regulating the delivery of vapor from said tubular connection to said induction pipe, a chamber between 95 said vaporizer and said induction pipe, a governing member movable in said chamber, said member being operatively connected to 100 said valve, said vaporizer, connection, valve, obturating member, chamber and governing member being arranged to be heated by the exhaust from said engine, and a tubular connection between said induction pipe 105 and said chamber back of said movable governing member.

5. In combination, an induction pipe through which a mixture of vapor and air is sucked to an internal combustion engine, 115 said induction pipe having a constricted part, a valve controlling the admission of air to said induction pipe, a fuel vaporizer, a tubular connection from said vaporizer to the constricted part of said induction pipe, 120 a manually adjustable obturating member for regulating the delivery of vapor from said tubular connection to said pipe, a governor comprising a member arranged between said vaporizer and said induction pipe, said member being influenced by the pressure of the mixture in said induction pipe, and a valve 125 operatively connected to said governor member, said valve being adapted to control the passage of fuel from said vaporizer to said 130

tubular connection, said vaporizer, connection, obturator and governor being arranged to be heated by the exhaust from said engine.

6. In combination, an induction pipe through which a mixture of fuel and air is sucked to an internal combustion engine, a fuel vaporizer, a governor device comprising a chamber between said vaporizer and said induction pipe, a governor member movable in said chamber and automatically controlled by the pressure of the mixture in said induction pipe, a valve operatively connected to said member, said vaporizer and governor device being arranged to be heated by the exhaust from said engine, and a tubular connection between said induction pipe and said chamber, one termination of said tubular connection being angularly shiftable in said induction pipe.
7. In combination, an induction pipe through which a mixture of fuel and air is sucked to an internal combustion engine, a passage for exhaust gases, a vaporizer in said passage, a tubular connection between said vaporizer and said induction pipe, said tubular connection extending through said

exhaust passage, a valve serving to control communication between said vaporizer and said tubular connection, said valve being in the zone heated by the exhaust gases, an obturating member for regulating delivery of vapor from said tubular connection to said induction pipe, said obturating member being in the zone heated by the exhaust gases, a chamber between and in communication with said vaporizer and said induction pipe, said chamber being thermally connected with said passage, and an automatically operating governor member movable in said chamber, said governor member being operatively connected to said valve and being controlled by the pressure in said induction pipe.

In testimony whereof we have signed our names to this specification in the presence of two subscribing witnesses.
